M. SETTER.

TELEPHONE TRANSMITTER.

APPLICATION FILED MAR. 19, 1917.

Patented Mar. 7, 1922.

FIG. 2.

FIG. 1.

Inventor
Michael Setter
Attala,
Attorney

UNITED STATES PATENT OFFICE.

MICHAEL SETTER, OF CHICAGO, ILLINOIS, ASSIGNOR TO AUTOMATIC ELECTRIC COMPANY, OF CHICAGO, ILLINOIS, A CORPORATION OF ILLINOIS.

TELEPHONE TRANSMITTER.

1,408,648.

Specification of Letters Patent. Patented Mar. 7, 1922.

Application filed March 19, 1917. Serial No. 155,664.

To all whom it may concern:

Be it known that I, MICHAEL SETTER, a citizen of the United States of America, and a resident of Chicago, county of Cook, and 5 State of Illinois, have invented certain new and useful Improvements in Telephone Transmitters, of which the following is a specification.

My invention relates in general to telephone transmitters and has for its object to 10 provide a transmitter structure in which certain of the parts, heretofore secured together by means of screw threads, are assembled by a "press fit," and are held together 15 solely by friction. This construction eliminates a large number of expensive screw machine operations in building the transmitter and thereby greatly reduces the first cost of the finished article, without however in 20 any way detracting from its durability or efficiency in operation.

The methods employed in carrying out the foregoing and other useful objects will be explained fully hereinafter, reference being 25 had to the accompanying drawing, in which Fig. 1 is a back view of a complete transmitter, and Fig. 2 is a cross section on the line M—M of Fig. 1.

Referring to the drawing the reference 30 character 1 designates the usual mouthpiece screwed into a threaded opening in the face plate 2. The face plate 2 is provided with a rearwardly projecting circular rim 5 within which is held by friction a heavy flanged ring 4, seen most clearly in Fig. 1. The metal bridge piece 3 is formed integrally with the ring 4 and acts as a support for the elements of the microphone. This latter comprises the carbon electrodes 8 and 21 35 and the chamber 6 partially filled with the comminuted carbon 11. The rear electrode 8 is secured to a metal disk 7 which is provided with a central screw threaded stem 9. The chamber 6 is simply a plain cup drawn 40 preferably from brass, is lined with insulating material, and is provided with a central aperture in the bottom. The stem 9 passes through this hole and a corresponding bushed aperture in the bridge 3, and the 45 nut 10 is screwed down to clamp the whole together. The chamber 6 and the nut 10 are 50 preferably insulated from the bridge 3 by means of washers of empire cloth.

The front electrode 21 is affixed to a metal disk 14 which has in front a tubular portion

16 and a central screw threaded stem 22. A mica diaphragm 13 fits over the tubular portion 16 and is held in place by a conical aluminum ring or washer 15, which latter fits tightly over the tube 16 and is further 60 secured by upsetting the edge of the tube. A metal clamping ring 12 fits tightly over the rim of the chamber 6 and the mica diaphragm is securely held between the edge of the chamber and the said ring. 65

The usual metal diaphragm 20 rests against an insulating ring 19 on the back of the face plate 2, and has at the center a hole through which is passed the stem 22. By means of nuts 17 and 18 the stem 22 is 70 rigidly secured to the diaphragm. The damping spring comprising two members 23 and 24 is attached to the ring 4 by means of screws 25 and 26. The extremities of these spring members 23 and 24 press against the 75 diaphragm 20 as shown in Fig. 2, there being a felt washer interposed between the diaphragm and the end of each spring.

To enable the microphone to be connected in a telephone circuit, a screw 28 and a binding post 29 are provided, the latter being connected with the front electrode by means of a sleeved conductor one end of which is clamped under the nut 17. 80

In assembling the various parts of the 85 transmitter, the elements of the microphone should be mounted on the bridge before the latter is attached to the face plate. Thus the chamber or cup 6 and the rear electrode may first be secured to the bridge by means 90 of the nut 10 which is screwed down on the stem 9. The front electrode and the mica diaphragm are then assembled, being held together as before mentioned by the aluminum ring 15 which is forced on over the 95 tube 16, the edge of the latter being then upset for further security. The proper quantity of granular carbon is then placed in the chamber and the mica diaphragm is placed in position across the top of the chamber. The clamping ring 12 is now forced on under pressure and grips the edge of the mica diaphragm between its flanged inner periphery and the edge of the chamber. The bridge and the parts carried thereby being 100 assembled, the nut 17 is screwed onto the stem 22 the proper distance, the diaphragm 20 is slipped over the end of the stem, and the ring 4 and face plate 2 are then forced together under pressure by special ma- 110

chinery. After this is done the remaining parts are assembled in any desired order to form the finished transmitter.

It will be observed from the foregoing 5 that certain important parts of the transmitter, including the ring 4 and face plate 2, the chamber 3 and clamping ring 12, and the member 14 with the aluminum ring 15, are forced together preferably under considerable pressure, and when once assembled are practically inseparable by any ordinary means. In addition to the great saving in the 10 cost of manufacture, this construction is of advantage in that it prevents tampering 15 with the instrument when in service for the purpose of making adjustments. It has been found impracticable to attempt such adjustments in service and when they seem to be necessary it is intended that the transmitter 20 be shipped to the manufacturer, where special devices are provided for taking it apart.

It will be observed further that in my improved transmitter the front or movable electrode is mounted on a member 14 which comprises in part a tube or shell 16, and that the mica diaphragm 13 is clamped between the member 14 and a conical aluminum washer 15, this method of construction being designed especially for the purpose of reducing 25 the weight of the moving parts. This saving in weight is of importance; for by reducing the inertia of the moving parts they are enabled to respond more readily to the vibrations caused by the impinging of 30 the air currents on the main diaphragm, and the operation of the transmitter is therefore greatly improved.

Having described my invention what I consider to be new and desire to have protected by Letters Patent will be pointed out 40 in the appended claims.

What I claim as my invention is:—

1. In a telephone transmitter, a face plate, and a microphone supporting bridge, the 45 said bridge and face plate being forced together and held solely by friction.

2. A transmitter structure involving a face plate provided with a rearwardly extending rim, and a bridged ring slightly 50 larger in outside diameter than the inside diameter of said rim, the said ring and face plate being forced together under pressure.

3. A transmitter structure comprising a circular face plate and an electrode supporting member, the two being adapted to be fitted together to form a frame for supporting the microphone parts, and substantially smooth, concentric curved surfaces on the said member and face plate cooperating to 55 hold the said member and face plate rigidly together by the friction between their own surfaces.

4. In a telephone transmitter, a microphone chamber, containing resistance vary-

ing material, means for closing one end of 65 said chamber, and a clamping ring for holding said means in position, frictional surfaces substantially smooth, said ring being forced over the end of said chamber and being held in place by friction between said surfaces. 70

5. In a transmitter, an electrode having a central stem, a perforated diaphragm fitted over said stem, and a retaining washer forced over said stem and held thereon by upsetting the edge of the stem to thereby hold 75 said diaphragm in place.

6. In a telephone transmitter, a microphone, a support for said microphone consisting of a plurality of concentrically arranged parts assembled in pairs, substantially smooth frictional surfaces on said parts, the parts of each pair being forced together under pressure and held by friction between said surfaces. 80

7. A non-demountable transmitter structure comprising a plurality of concentrically arranged parts in pairs, the parts of each pair being permanently secured together by means of friction, and a microphone, said structure for supporting said microphone. 85

8. In a telephone transmitter, a movable electrode, a mounting for said electrode comprising a shell having a head to which the electrode is attached, a conical aluminum washer tightly fitted over said shell and held 90 thereon by upsetting the edge of the shell, and a diaphragm clamped between the said head and the said washer.

9. In a telephone transmitter, a tubular shell having a head portion closing one end, 100 an electrode attached to said head, a conical aluminum washer fitted over said shell and riveted thereon by upsetting the projecting edge of the shell, and a diaphragm clamped between the said head and the said washer. 105

10. In a telephone transmitter, a movable electrode and a support therefor, the said support comprising a member in the form of a tubular rivet, the said electrode being attached to the head thereof, an aluminum 110 washer riveted on the tubular portion thereof, and a diaphragm clamped between the said head portion and the said washer.

11. In a telephone transmitter, a microphonic cell comprising a cup containing resistance varying material, an electrode mounted in the bottom of said cup, a diaphragm, a ring for fastening said diaphragm over the opening of said cup, said ring adapted to fit over only the upper edge of 120 the wall of the cup and so constructed as to fit tightly thereover, said ring forced over the rim of the cup in such a manner that it may be removed without changing its shape. 115

Signed by me at Chicago, Cook county, 125 State of Illinois, this 15th day of March, 1917.

MICHAEL SETTER.
